CHARLES WALES, OF NEW HAVEN, CONNECTICUT, ASSIGNEE TO FEDERAL ADDING MACHINE CORPORATION, OF NEW YORK, N. Y., A CORPORATION OF NEW JERSEY.

MACHINE HAVING SLIDING CARRIAGE.

1,344,837.

Specification of Letters Patent. Patented June 29, 1920.

Application filed November 5, 1919. Serial No. 335,860.

To all whom it may concern:

Be it known that I, CHARLES WALES, a citizen of the United States, residing at New Haven, county of New Haven, State of Connecticut, have invented a certain new and useful improvement in Machines Having Sliding Carriages, of which the following is a full, clear, and exact description.

My invention relates to machines having sliding carriages and has for its object to provide a track and a sheet metal slide therefor having its downward and side thrusts resisted by anti-friction devices.

One feature of my invention is a slide having a Z-shaped body portion with vertical extensions. Another feature of my invention is the use with such a slide of anti-friction devices for resisting side thrusts; and another feature is the use with such a slide of anti-friction devices for receiving the vertical thrust.

The following is a description of my invention, reference being had to the accompanying drawings, in which—

Figure 1 is a side elevation of a sliding carriage and a portion of a machine frame provided with tracks for the slide of the carriage;

Fig. 2 is a front view of portions of machines including the track and the parts to which it is secured;

Fig. 3 is a perspective view of a track and the slide carried thereby, and

Fig. 4 shows a perspective view of the portion of the machine to which the track is removably attached and means for locking it in place.

Referring more particularly to the drawings, 1 represents the frame of an adding machine having a track supporting member 2, provided with openings 3, which openings are provided on their left-hand sides with recesses 4 in which rest the shanks 5 of studs having enlarged heads 6, said studs being secured to the track member 7. The track member is positioned upon the supporting member 2 so that the heads of the studs 4 extend through the enlargements of the opening 3 and are then moved to the left so that the shanks 5 lie in the smaller portions of the openings, whereupon the track mem-

ber is locked in position by a latch 8 pivoted at 9. The features whereby the track member is secured to the machine do not however constitute a part of my invention, 55 being features commonly employed in calculating machines.

The track member is made of sheet metal and consists of a vertical portion bent somewhat into the form of a C so as to provide 60 a depending thrust flange 10 and an upwardly extending retaining flange 11. The inner surface of the depending flange 10 provides a vertical track for the anti-friction devices hereinafter described, while the 65 inner surface 12 on the lower portion of the back of the C provides a similar vertical track. The horizontal surface 13 within the lower portion of the C constitutes a horizontal track for anti-friction devices, and the 70 upwardly projecting flange 11 constitutes a retaining member for the slide. 14 is a slide, the body portion of which as shown in Fig. 1 is shaped somewhat like a Z somewhat elongated and the upper and lower ends of 75 which are provided with vertical flanges 15 and 16, the upper right-hand surface (Fig. 1) opposing the inner surface of the flange 10 constituting a thrust bearing, while the left-hand surface of the part 16 (Fig. 1) 80 opposing the surface 12 constitutes another thrust bearing. The lower surface of the Z opposed to the surface 13 constitutes a third or horizontal thrust bearing surface. Between the thrust bearing surface on the 85 flange 15 and the track on the flange 10 and supported by the top of the Z are anti-friction rollers 17, consisting of two heads connected by a vertical shaft 18, the heads being spaced away to admit a bar 19 having 90 notches 20, as shown in Figs. 5 and 6. The bar 19 spaces the two anti-friction members 17 apart by a definite distance and the anti-friction members 17 running upon the track formed by the flange 10 and engaging the 95 thrust surface on the flange 15, eliminate sliding friction between the slide and track member at the upper end of the slide. The slide is provided with a pin 21 at each end which are adapted to engage the ends of the 100 bar 19 after the slide has moved a predetermined distance and carry said bar and the

- anti-friction devices 17 along with it. The track is also provided with pins 22 at each end which, after bar 19 has been moved a certain distance in one direction or the other, prevent its further movement and also block the continued movement of the slide. Between the track 12 and the opposing surface of the flange 16 a similar anti-friction device to that shown in Figs. 5 and 6 is also placed, being supported by the horizontal track 13, the axes of the anti-friction members being also vertical as shown in dots in Fig. 2. Upon the horizontal track 13 are also placed short cylindrical rollers 23, one on each side of the device shown in Figs. 5 and 6, so as to be spaced apart by the member 19, which rollers engage the horizontal track and also engage the horizontal undersurface on the bottom of the Z, thus supporting the slide. The united anti-friction rollers 17 and the rollers 23 at the bottom of the slide thus eliminate sliding friction between the slide and track at that point, the rollers 23 supporting the slide and resisting its downward thrust at two points, while the rollers 17 with their vertical axes resist the side thrusts at two points. Pins 21' and 22' confine the anti-friction devices at the lower edge of the slide acting in a manner similar to pins 21 and 22. The slide is provided with ears 24, to which is secured the frame of the carriage proper, which may be of any desired construction. The slide carries a plate 25 which supports a pin 26, which acts as a stop for the slide and carriage, limiting the movement of the same by engaging the side plates 27 of the carriage when the same has reached its proper limit in either direction.
- 40 In constructing the machine the parts are assembled as shown, whereupon the slide with the carriage supported thereby is free to move in one direction or the other without sliding friction, the rollers 23 resisting the downward thrust while the rollers 17 at top and bottom resist the side thrust. With the Z-shaped slide thus guided and supported, the slide can be made of sheet metal with resulting simplicity and cheapness in manufacture and accuracy in result.
- 45 As will be evident to those skilled in the art, my invention permits of various modifications without departing from the spirit thereof or the scope of the appended claims.
- 50 65 What I claim is:
1. In a machine having a sliding carriage, the combination of a track member having at its top an overhanging flange and at its bottom upwardly projecting retaining means, a slide therein having at its upper and lower ends oppositely facing vertical surfaces and having at its lower portion a downwardly facing surface adjacent to the upper edge of the lower vertical surface, in combination with side-thrust anti-friction members between said vertical surfaces and said track member, and supporting anti-friction members between said downwardly facing surface and said track member, the upper end of said slide tending to move toward the overhanging flange. 70
  2. In a machine having a sliding carriage, the combination of a track member having at its top an overhanging flange and at its bottom upwardly projecting retaining means, a slide therein having at its upper and lower ends oppositely facing vertical surfaces and having at its lower portion a downwardly facing surface adjacent to the upper edge of the lower vertical surface, in combination with side-thrust anti-friction members between said vertical surfaces and said track member, and supporting anti-friction members between said downwardly facing surface and said track member, the upper end of said slide tending to move toward the overhanging flange, the side-thrust members being rollers having vertical axes, and spacing means for said rollers. 80
  3. In a machine having a sliding carriage, the combination of a track member having at its top an overhanging flange and at its bottom upwardly projecting retaining means, a slide therein having at its upper and lower ends oppositely facing vertical surfaces and having at its lower portion a downwardly facing surface adjacent to the upper edge of the lower vertical surface, in combination with side-thrust anti-friction members between said vertical surfaces and said track member, and supporting anti-friction members between said downwardly facing surface and said track member, the upper end of said slide tending to move toward the overhanging flange, the side-thrust members being rollers having vertical axes, and spacing means for said rollers. 90
  4. In a machine having a sliding carriage, the combination of a track member having at its top an overhanging flange and at its bottom upwardly projecting retaining means, a slide therein having at its upper and lower ends oppositely facing vertical surfaces and having at its lower portion a downwardly facing surface adjacent to the upper edge of the lower vertical surface, in combination with side-thrust anti-friction members between said vertical surfaces and said track member, and supporting anti-friction members between said downwardly facing surface and said track member, the upper end of said slide tending to move toward the overhanging flange, the side-thrust members being rollers having vertical axes, and the supporting members being rollers having longitudinal axes, and spacing means for said rollers. 100
  5. In a machine having a sliding carriage, the combination of a track member having at its top an overhanging flange and at its bottom upwardly projecting retaining means, a slide therein having at its upper and lower ends oppositely facing vertical surfaces and having at its lower portion a downwardly facing surface adjacent to the upper edge of the lower vertical surface, in combination with side-thrust anti-friction members between said vertical surfaces and said track member, and supporting anti-friction members between said downwardly facing surface and said track member, the upper end of said slide tending to move toward the overhanging flange, and stops carried by the ends of said track member and slide coacting with said anti-friction members. 110
  6. In a device having a sliding carriage, the combination of a track member having at its top a depending flange forming a ver- 120

tical track and at its lower part a surface forming a vertical track facing in the opposite direction from said first-mentioned track, and a horizontal surface forming a horizontal track with a Z-shaped sheet metal slide having on its top and bottom flat surfaces, the lower surface being above said

horizontal track, and at its extremities vertical portions parallel to said vertical tracks respectively, and anti-friction members between said vertical portions and said vertical tracks and between said bottom surface and said horizontal track.
